PANTOGRAPH LUBRICATOR

William Schaake, Pittsburgh, Pa., assignor to
 Westinghouse Electric & Manufacturing Company,
 East Pittsburgh, Pa., a corporation of
 Pennsylvania

Application February 14, 1934, Serial No. 711,124

7 Claims. (Cl. 184—15)

My invention relates, generally, to current collectors for electric vehicles and it has particular relation to lubricating devices for pantograph slider shoes.

5 In the operation of current collectors for electric vehicles, in which a slider shoe of the pantograph type is used, an abrasive action results due to the shoe moving along the overhead conductor or trolley wire. Ordinarily, the slider shoe is composed of steel, and this shoe in sliding contact with a trolley wire of copper or the like will cause a very rapid wearing action both on the trolley wire and on the slider shoe.

In order to reduce to a minimum this abrasive action, many systems have been proposed for providing a lubricating medium between the pantograph slider shoe and the trolley wire. Some of these devices involved the use of a wick which is arranged to dip in a fluid lubricant, and, 15 by capillary attraction, the lubricant is caused to rise and to be applied to the surfaces which are in contact and which are to be lubricated. It has also been proposed to provide a liquid or semi-solid lubricant in grooves in the slider shoe. 20 Still other modifications comprise the use of auxiliary slider shoes containing either a liquid or a solid lubricant and caused to resiliently engage the trolley wire either in front of or behind the slider shoe.

25 At the present time, it is well known that electric vehicles, such as electric locomotives, with which pantograph collecting devices are used, travel at relatively high speeds, such as 80 to 100 miles per hour. When a lubricating device is used on a pantograph which is to travel at such speeds, it must be such as will effectively perform its lubricating function and still will not interfere with the satisfactory operation of the current collector. Due to the high speed and slight irregularities which always exist in the construction 30 of the overhead conductor system and the track, it is highly desirable that the lubricating device shall have a minimum of inertia and be relatively freely movable so that it may be continuously maintained in engagement with the trolley wire under all conditions.

Furthermore, the lubricating device should be so positioned that its operation will not be affected by the relatively high wind pressures which 35 exist when the electric vehicle is travelling at the relatively high speeds. It has been found that the effects of the high wind pressure may be such as to cause the current collecting equipment to be moved out of contact engagement with the trolley wire with the result that considerable arc-

ing exists and erratic operation of the vehicle follows.

The object of my invention, generally stated, is to provide a lubricating device for pantograph slider shoes which shall be simple and efficient in operation and which may be readily and economically manufactured and installed. 5

The principal object of my invention is to provide for reducing the abrasive action between a pantograph slider shoe and a trolley wire as the shoe is moved along in engagement with the wire. 10

Another object of my invention is to provide for reducing the inertia of a pantograph lubricating device to a minimum, in order to permit the current collector with which it is associated 15 to more readily follow and remain in engagement with the trolley wire.

Still another object of my invention is to provide for protecting the pantograph lubricator from coming into engagement with any obstruction which might tear it from its mounting. 20

A further object of my invention is to provide for maintaining a pantograph lubricating device in continuous engagement with an overhead trolley wire under all conditions of operation. 25

Other objects of my invention will, in part, be obvious and, in part, appear hereinafter. My invention, accordingly, is disclosed in the embodiment hereof shown in the accompanying drawing, and comprises the features of construction, combination of elements and arrangement of parts which will be exemplified in the construction hereinafter set forth, and the scope of the application of which will be indicated in the appended claims. 30

35 For a more complete understanding of the nature and scope of my invention, reference may be had to the following detailed description taken in connection with the accompanying drawing, in which:

Figure 1 is a view, in side elevation, of a concrete embodiment of my invention;

Fig. 2 is an enlarged top plan view of the major portion of the slider shoe shown in Fig. 1;

Fig. 3 is a longitudinal sectional view of the 45 pantograph slider shoe showing the details of construction;

Fig. 4 is an enlarged sectional view taken along the line IV—IV of Fig. 3; and

Fig. 5 is another enlarged sectional view taken 50 along the line V—V of Fig. 3.

Referring now particularly to Figs. 1, 2 and 3 of the drawing, the reference character 10 designates a pantograph slider shoe having a down-turned flanged section, as is more clearly illus- 55

trated in Figs. 4 and 5 of the drawing. The slider shoe 10 is provided with the customary end horns 11 and 12, which serve to prevent the current collecting apparatus from becoming entangled with the overhead conductor or trolley wire 13, which, under normal conditions, is centrally located with respect to the slider shoe 10.

It will be understood that the slider shoe 10 may be supported by the customary pantograph structure, which, since it forms no part of this invention, is shown only insofar as is necessary to indicate that the upper portions 14 and 15 thereof may be secured to the slider shoe 10 by means of transversely extending bolts 16 and 17.

In order to provide for reducing the wearing or abrasive action caused by the frictional engagement of the upper surface of the slider shoe 10 with the trolley wire 13 as it is moved, for instance, in the direction indicated by the arrow 18, a lubricating device shown generally at 19 is provided. The lubricating device 19 comprises an articulated solid lubricating member 20, which may be composed of three sections 21, 22 and 23, as shown in Fig. 3 for reducing the likelihood of breakage and for providing greater flexibility in operation. As illustrated, the lubricating member 20 projects upwardly through an aperture 24, which, in this instance, is centrally located in the upper flat surface of the slider shoe 10 and midway between the leading and trailing edges thereof.

As shown in Fig. 1 of the drawing, the upper or rubbing surface of the lubricating member 20 is normally in the same plane as the contact surface of the slider shoe 10 when both are in engagement with the trolley wire 13. However, when the current collector is out of engagement with the trolley wire 13, the upper surface of the lubricating member 20 will be positioned slightly above the contact surface of the slider shoe 10, as illustrated in Fig. 3 of the drawing, by means which will be presently described.

Referring now particularly to Figs. 3 and 5 of the drawing, it will be observed that the articulated sections 21, 22 and 23 of the lubricating member 20 are positioned in a holder 27, and may be secured therein by means of cotter pins 28. The holder 27 is preferably composed of steel and is formed into a rectangular box-like structure which is arranged to be mounted underneath the slider shoe 10 and aligned with the opening 24 therein. In order to limit the upward movement of the holder 27 and thereby the upward movement of the lubricating member 20, the holder 27 is provided with a flange 29 around the upper edges thereof and extending outwardly, as is more clearly illustrated in Fig. 5 of the drawing. Since the inner dimensions of the aperture 24 are the same as the inner dimensions of the holder 27, it will be readily understood that the upward movement of the latter may be limited by means of the flange 29.

As set forth hereinbefore, it is desirable to so mount the lubricating member 20 that it will remain in engagement with the overhead conductor or trolley wire 13 under substantially all operating conditions. For this purpose, the holder 27 is resiliently mounted by means of a pair of flat or leaf support springs 31 and 32 which are secured to the under surface of the holder 27 by means of rivets 33. It will be observed that the support springs 31 and 32 are secured to bolts 35 and 36, which are located near the ends of the slider shoe 10, and which extend transversely through the down-turned flanged

portions thereof. Since the support springs 31 and 32 are not as wide as the inner transverse dimensions of the slider shoe 10, tubular spacers 38 are provided, together with washers 39, in order to maintain the support springs 31 and 32 in the desired positions.

In the event that any of the sections 21, 22 and 23 of the lubricating member 20 become worn to such an extent that they no longer project above the surface of the slider shoe 10, it will be readily understood that they may be replaced merely by withdrawing the cotter pin 28 individual thereto and inserting a new section. It may also be desirable to reduce the relative depth of the holder 27 from that shown, so that a greater portion of the lubricating member 20 may be subject to wear than would otherwise be possible. This, however, it will be understood, is merely a matter of design which will be governed by the conditions which are most applicable thereto.

Since the lubricating device 19 is located substantially entirely within the confines of the slider shoe 10, there is little, if any, likelihood that it will become dislodged due to engagement with any obstruction, which might otherwise be the case if it were mounted separate from the slider shoe 10. In view of the fact that a minimum of supporting structure is required for the lubricating member 20, when it is constructed and located as herein described, it will be obvious that the inertia of the entire lubricating device 19 has been practically reduced to the absolute minimum. There will, therefore, be a minimum of interference with the operation of the slider shoe 10, as it is carried by the pantograph structure to maintain it in engagement with the trolley wire 13 at the high speeds which are now customary for the operation of electric vehicles.

Since certain further changes may be made in the above construction and different embodiments of the invention may be made without departing from the scope thereof, it is intended that all matter contained in the above description or shown in the accompanying drawing shall be interpreted as illustrative and not in a limiting sense.

I claim as my invention:

1. Current collecting means for an electric vehicle comprising, in combination, an elongated pantograph slider shoe having a down-turned channel section for engaging an overhead trolley wire substantially at right angles to the longitudinal axis of the shoe, the contact surface of said shoe being provided with an aperture, a holder positioned underneath the shoe and aligned with and movable relative to said aperture, retaining means extending through said down-turned channel section near each end thereof, support springs attached to the ends of said holder and secured to said retaining means, and a solid lubricating member carried by said holder to extend upwardly through said aperture and disposed to engage said trolley wire.

2. Current collecting means for an electric vehicle comprising, in combination, an elongated pantograph slider shoe having a down-turned channel section for engaging an overhead trolley wire substantially at right angles to the longitudinal axis of the shoe, the contact surface of said shoe being provided with a centrally located aperture, a holder positioned beneath and aligned with and movable relative to said aperture, said holder being provided with a flange positioned to

limit the upward movement thereof beyond a predetermined extent, a bolt extending through said down-turned channel section near each end thereof, flat support springs attached to the ends 5 of said holder and secured to said bolts, and an articulated solid lubricating member carried by said holder and positioned to extend upwardly through said aperture for engaging said trolley wire.

10 3. A current collector for an electric vehicle comprising, in combination, a pantograph slider shoe for engaging an overhead trolley wire having an aperture in the contact surface thereof, a holder aligned with and movable relative to said 15 aperture, resilient means for biasing said holder upwardly, and an articulated lubricating member of solid material carried by said holder and projecting through said aperture to engage said trolley wire.

20 4. A current collector for an electric vehicle comprising, in combination, a pantograph slider shoe for engaging an overhead trolley wire having an aperture in the contact surface thereof, a holder aligned with and movable relative to said 25 aperture, leaf spring means for biasing said holder upwardly, and a solid lubricating member carried by said holder and extending through said aperture to engage said trolley wire.

5. A current collector for an electric vehicle 30 comprising, in combination, a pantograph slider shoe for engaging an overhead trolley wire having

an aperture in the contact surface thereof, a holder aligned with and movable relative to said aperture, leaf spring means for biasing said holder upwardly, and an articulated lubricating member of solid material carried by said holder and projecting through said aperture to engage said trolley wire. 5

6. A current collector for an electric vehicle comprising, in combination, a pantograph slider shoe for engaging an overhead trolley wire having an aperture in the contact surface thereof, a holder aligned with and movable relative to said aperture, leaf spring means secured to each end of said holder and to the underside of said slider shoe for biasing said holder upwardly, and a solid lubricating member carried by said holder and extending through said aperture to engage said trolley wire. 10

7. A current collector for an electric vehicle comprising, in combination, a pantograph slider shoe for engaging an overhead trolley wire having an aperture in the contact surface thereof, a holder aligned with and movable relative to said aperture, leaf spring means secured to each end of said holder and to the underside of said slider shoe for biasing said holder upwardly, and an articulated lubricating member of solid material carried by said holder and projecting through said aperture to engage said trolley wire. 15
